UNITED STATES PATENT OFFICE

THOMAS L. FITZPATRICK, OF KENOSHA, WISCONSIN

AUTOMATIC CONTROL FOR INTERNAL-COMBUSTION ENGINES

Application filed October 14, 1927. Serial No. 226,228.

The invention relates to an improved automatic control for internal combustion engines especially such as are used on automobiles, an object of the invention being to provide a 5 simple and efficient device of this character whereby fuel for said engine is automatically controlled by the ascent or descent of a grade by said automobile.

Another object of the invention is to provide such a control for an automobile engine which is unaffected by the vibration or motion of the automobile and is also sufficiently flexible in operation to meet the various conditions arising.

Another object of the invention is to provide a device of this character by means of which the engine is automatically controlled by the clutch pedal of the automobile.

Another object of the invention is the provision of a device of this character which will dispense with the necessity or desirability of a foot accelerator thereby leaving both feet of the operator free for control of other parts.

Other objects will appear hereinafter.

25 The invention consists in the combination and arrangement of parts hereinafter described and claimed.

The invention will be best understood by reference to the accompanying drawings 30 forming a part of this specification and in which—

Fig. 1 is a partial side view, with portions broken away, of the forward portion of an automobile equipped with a device embodying the invention;

Fig. 2 an enlarged vertical longitudinal section taken through a control tank employed in the construction;

Fig. 3 a top plan view of said tank with the 40 cover thereof removed;

Fig. 4 a sectional view taken substantially on line 4—4 of Fig. 1;

Fig. 5 a view at right angles to Fig. 4; and

Fig. 6 a view similar to Fig. 2 but showing 45 the parts in inclined positions such as are assumed in ascending a grade.

The preferred form of construction as illustrated in the drawings comprises the usual motor or engine block 11 provided with the usual inlet manifold 12 connected in the

usual manner with the usual carburetor 13. A suitable liquid tank or container 15 is mounted upon the engine block 11 and provided with a removable cover 16. The tank 15 constitutes a control tank and contains a 55 suitable amount of liquid, preferably plain water in the summer time and a non-freezing mixture of water in the winter time in freezing climates.

Two tubular guide members 17 and 18 are 60 arranged in the tank 15 projecting upwardly from the bottom thereof, the forward guide member 17 being cylindrical in form and the rear guide member 18 being upwardly tapering in form. The usual operating arm 21 mounted at the lower end of the usual throttle lever 22 of the automobile is connected by a flexible wire or cable 23, running over a guide pulley 24 on a bracket 25 on the carburetor casing 13, with a float 29 in the control tank 70 15. The wire or cable 23 extends upwardly through the guide tube 17 and is provided at its upper end with a loop or eyelet 26 connected with a pair of cross wires 27 which have their ends secured in suitable lugs 28 provided around the upper periphery of the float 29. This connection provides a universal flexible connection between the float 29 and the wire 23 which permits the float to 75 adjust itself to any desired position of the tank 15 without placing undue strain or binding action on the cable or wire 23. The float 29 is of sufficient size to effect a comparatively large displacement of the liquid in tank 15 when depressed therein, so that depression of said float materially raises the level of the liquid in said tank. The float 29 is also of sufficient height so that it will reach the bottom of said tank before the liquid flows over the top of said float, thereby preventing accidental or unintentional escape of the liquid through the hollow center of the float. The hollow center of the float is provided to permit free upward and downward movement thereof on the guide member 17. By this arrangement it will be noted that operation or manipulation of the throttle lever 22 simply depresses or raises the float 29 in the 80 control tank 15.

A second float 33 having a tapered central 100

opening 34 is slidably mounted on the guide member 18. The float 33 is provided with securing lugs 35 at its upper edges and crossed wires 36 having a universal flexible connection with wire 37 passing downwardly through the tube 18. The other end of wire 37 is secured to one side of the lever arm 41 operatively connected as indicated with the throttle or butterfly valve 42 located in the intake of the engine. By this arrangement it will be noted that when the level of liquid in tank 15 is raised as indicated above, an upward thrust will be exerted on float 33 and this upward thrust will elevate the end of lever arm 41 and thus operate the throttle valve 42 to control the operation of the engine in the usual way. In this way a flexible control for the engine is provided which will gradually change the speed of the engine and thus prevent sudden variations therein and consequent shocks and jars to the automobile. It will also be noted that the operator can set his throttle lever to admit the desired amount of fuel to the engine at any desired speed.

25 A number of baffle plates or partitions 43 are mounted in the tank 15 between the floats therein and around the float 33, said partitions or baffle plates being provided with openings 44 caused by striking ribs or projections 45 therefrom. These perforated partitions or baffle plates have a tendency to maintain the liquid in the tank 15 in a substantially motionless state during operation of the automobile and therefore affected only 35 by the operation of the floats therein. This tends to insure uniformity of operation of the device.

In order to provide an automatic connection with the clutch of the automobile I provide a push rod 50, having one end connected to the clutch pedal 51 through a slot and pin connection 52, and its forward end slidably mounted in the bracket 53 on the carburetor 13. The forward end of the push rod 50 carries a cam member 54 having an inclined forward end, as shown, and engaging under a roller 55 on the end of the lever arm 56 of the throttle valve control lever mentioned above. The lower portion 57 of said cam member 50 operates through the guide bracket 53, as shown, and whereby said cam member is guided during its operation. The push rod 50 is provided at 58 with a hinge joint to permit of a limited amount of flexing of the same as the clutch pedal is operated. A turn buckle 59 provides suitable adjustments in said push rod. By this arrangement when the clutch pedal 51 is depressed, to disengage the clutch, the cam member 54 will move forward and raise the arm 56 thereby closing the throttle valve 42 and shutting off the flow of fuel to the motor or engine. When the pedal returns to normal, the cam is withdrawn and the 65 float 33 returns the throttle valve to its proper

position for feeding gas to the engine under driving conditions.

In Fig. 6 of the drawings I have shown the position assumed by the parts when the automobile is ascending a grade. This causes the liquid to flow into the rear portion of the tank 15 thereby raising the level at this point and causing the float 33 to rise and open the throttle valve 42 thereby supplying increased fuel to the engine on an up grade. The reverse action takes place on the down grade thereby conserving fuel when not needed. In this manner it will be noted that the fuel supply will be automatically controlled by the inclination of the automobile in ascending or descending a grade, thus eliminating necessity of manual control under such circumstances. It will also be noted that the necessity of a foot accelerator is dispensed with, thereby leaving the right foot of the operator free for manipulation of the foot brake if desired. This has a tendency to facilitate starting of the automobile on up grades and eliminates shocks and jars under such circumstances thereby lengthening the life of the working parts of the automobile.

While I have illustrated and described the preferred form of construction for carrying my invention into effect, this is capable of variation and modification without departing from the spirit of the invention. I therefore do not wish to be limited to the precise details disclosed but desire to avail myself of such variations and modifications as come within the scope of the appended claims.

I claim:

1. The combination with an internal combustion engine having a throttle valve and a throttle lever, of a float, operable yieldable connection between said lever and said valve.
2. The combination with an internal combustion engine having a throttle valve and throttle lever, of a liquid containing tank; a float in said tank; means connected with said throttle lever for varying the level of liquid in said tank; and an operative connection between said float and said throttle valve.
3. The combination with an internal combustion engine having a throttle valve and a throttle lever, of a liquid containing tank; a float in said tank; a second float in said tank of a size to raise the level of liquid upon depression therein; an operative connection between said second float and said throttle lever; and an operative connection between said float and said throttle valve.
4. The combination with an internal combustion engine having a throttle valve and a throttle lever; of a liquid containing tank, a float in said tank, a second float in said tank of a size to raise the level of liquid upon depression therein, an operative connection between said second float and said throttle lever, an operative connection between said first float and said throttle valve, and a per-

forated partition in said tank between said floats.

5. The combination with an internal combustion engine comprising an engine block, a carburetor, a throttle valve and a throttle lever, of a liquid containing tank mounted upon said engine block, a float in said tank operatively connected with said throttle lever and of a size to raise the level of said liquid 10 in said tank upon depression therein, and a second float in said tank operatively connected with said throttle lever.

6. The combination with an internal combustion engine comprising an engine block, a carburetor, a throttle valve and a throttle lever, of a liquid containing tank mounted upon said engine block, a float in said tank operatively connected with said throttle lever and of a size to raise the level of said liquid 15 20 in said tank upon depression therein; a second float in said tank operatively connected with said throttle lever; and a perforated partition in said tank between said floats.

In testimony whereof I affix my signature 25 at 5054 Plankinton Building, Milwaukee, Wis.
